VALVE GUARD

William H. Buck, Scottdale, Pa.

Application February 18, 1936, Serial No. 64,565

12 Claims. (Cl. 137—13)

This invention relates to new and useful improvements in devices for preventing unauthorized persons from tampering with water, oil, gas or other gaseous or liquid control valves.

As is well known, pipe lines employed to distribute gaseous or liquid commodities from the larger supply lines or "mains" to buildings, homes and other places for consumption or use are for the most part provided with shut off valves so located that the supply of gas or liquid to a particular building, house or the like may be turned off at the will of the service company in the event that the customer becomes delinquent in payment for the service, the premises vacated or the service no longer desired. Up to the present time, however, it has been comparatively easy for unauthorized persons to gain access to these valves and restore the supply of gas or liquid without the knowledge or consent of the service company, and the theft and other unauthorized use and consumption of gases and liquids in this manner results in the loss of many thousands of dollars annually to the producers and suppliers of these commodities.

Accordingly, the principal object of the present invention is to provide a device which may be effectively employed by service companies to prevent unauthorized persons from successfully gaining access to the shut-off valves in branch distribution pipe lines. A more particular object of the present invention is to provide a device of the character described which may be used in conjunction with standard fixtures without necessitating any re-designing or alteration of the present construction thereof, and a still further object is to provide a device of the present character together with means for concealing certain details of such device and permanently record any attempt made to tamper with the shut-off valve.

These and other objects of the invention and the details of construction thereof are set forth hereinafter and shown in the accompanying drawing, in which:

Fig. 1 is a fragmentary view in section vertically through a valve housing showing a device made in accordance with the present invention operatively associated with a gas or water valve and fixture.

Fig. 2 is a view in perspective of the device forming the subject matter of the invention.

Fig. 3 is a fragmentary view in perspective of a key, tool or like element for use in conjunction with the device disclosed in Fig. 2; and

Fig. 4 is a view in perspective of a seal and tell-tale element used in conjunction with the present invention.

Referring now more particularly to the drawing, reference numeral 1 designates generally a standard type of casing or housing commonly used by gas and water service companies to protect the valves in branch distribution pipe lines residing 5 several feet below the surface of the earth, and at the same time provide a means of ready access to said valves.

As shown, the valve housing 1 comprises an upper neck portion 2 and a lower wider skirt-like 10 portion 3 having outwardly projecting flanges 4 at its lower end to support said casing 1 in the vertical position shown. The wider skirt-like portion 3 is further provided with at least two diametrically opposed slots 5 therein which extend 15 upwardly from the bottom thereof to provide openings for the passage of a pipe line 6 of the size customarily employed to connect the distribution outlets of a building, house or the like with the "main" supply line. The casing 1 is positioned longitudinally of the pipe line 6 so that the shut-off valve 7 therein resides centrally within the lower skirt-like portion 3 in alignment with the neck portion 2 which extends upwardly to the surface of the earth and has its upper end 8 20 normally closed by means of a cover plate 9 removably secured in the closed position by means of a bolt or the like 10 which threadably engages a lug 11 on the outer wall of said neck portion 2 as shown in Fig. 1 of the drawing.

So far I have described the standard type of valve casing usually employed by gas and water companies to protect the shut-off valves in branch distribution pipe lines, and it will be observed that access to said valves may be readily had by merely 30 removing the cover or closure plate 9 at the upper end 8 of the neck portion 2, and inserting therein a wrench or other tool of sufficient length to actuate the valve 7. It will be obvious, however, that this construction renders these shut-off 35 valves accessible not only to persons authorized by the service companies but also to the general public and other unauthorized persons.

The invention therefore resides in providing a novel device which may be effectively employed 40 by gas and water service companies in conjunction with standard fixtures of the type previously described to prevent unauthorized persons from gaining access to the shut-off valves in branch pipe-lines, and referring particularly to Fig. 2 45 of the drawing reference numeral 12 designates generally a novel guard element comprising a top disk-like portion 13 and a plurality of slightly convex integral resilient fingers 14 of substantial width which project downwardly from 50

the latter at predetermined spaced intervals circumferentially thereof.

In the present instance the diameter of the top disk like portion 13 of the guard element 12 is 5 slightly less than that of the neck portion 2 of the casing 1 and the maximum diameter of the convex fingers 14 in their normal static relationship is slightly greater than that of said neck portion 2 so that when said guard element 12 is 10 inserted into the neck portion 2 in the manner shown in Fig. 1 of the drawing, said fingers 14 thereof will be compressed and accordingly exert an outward pressure or force against the inner wall of said neck 2 to retain said guard 15 12 firmly therein.

An opening or key way designated generally as 15 is formed centrally in the top portion 13 of the guard 12 and arranged to receive a key or like tool 16. The key or tool 16 comprises a 20 rod or shaft like portion 17 of substantial length having oppositely curving elements 18 projecting laterally from adjacent the lower end thereof as shown in Fig. 3 of the drawing, and the opening or key way 15 in the top portion 13 is similarly 25 formed to provide a circular central portion 19 and oppositely curving laterally projecting portions 20 arranged to receive respectively the rod or shaft portion 17 and oppositely curving projecting elements 18 of the tool or key 16. For 30 the purpose of concealing the particular configuration of the opening or key way 15 in the top disk like portion 13 of the guard 12, a de-structible disk 19 shown in Fig. 4 of the drawing, and composed of slater's felt, tar paper or 35 the like, is secured to the upper face of the disk-like portion 13 by means of any suitable adhesive substance as shown in Fig. 1.

The guard 12 may be effectively used by gas and water service companies to prevent unauthorized persons from gaining access to the valves in branch distribution pipe lines after the supply of gas or water to a particular outlet has been shut off by closing said valves and is preferably installed by the service company at the time the 40 particular valve 7 is shut off by inserting the same with the disk 19 secured thereto inwardly of the neck portion 2 of the valve casing 1 in the manner shown in Fig. 1 of the drawing to engage the lower extremities of the convex fingers 45 14 with the valve 7 or its handle, after which said casing 1 is closed by securing the cover plate 9 over the upper end 8 of said neck portion 2 thereof. It will be observed that the guard element 12 can be successfully removed from the 50 neck 2 of the casing 1 only by a person having a key or tool 16 which conforms substantially to the opening or key way 15 in the top 13 of said guard 12. To remove the guard 12 it is necessary to puncture or pierce the disk 19 so that 55 the key 16 may be inserted through the opening or key way 15 and rotated to engage the oppositely curving portions 18 of said key 16 with the under side of the top disk portion 13 of the guard, and inasmuch as said guard 12 cannot be 60 withdrawn from the neck 2 of the housing 1 without puncturing or permanently distorting the said disk 19, it will be obvious that any attempt to remove the guard to gain access to the 65 shut-off valve 7 will be indicated to the service company upon inspection. The keys 16 are of course retained in the sole custody of the service company and the disk 19 effectively conceals the 70 particular configuration of the key way 15 so that unauthorized persons are unable to deter-

mine the shape or form of tool that would be required to remove the guard 12 from the neck 2 for access to the shut-off valve 7.

It will be obvious that the specific configuration of the key way 15 and key 16 form no part 5 of the present invention other than to indicate that a key and key way should be provided which will be effective to prevent removal of the guard 12 from the casing 1 by any means other than a specifically designed key or like tool, and it 10 is further not intended that the invention in other respects be precisely limited to the details of construction herein set forth, but that changes and modifications may be incorporated therein 15 where within the scope of the annexed claims.

I claim:

1. A valve guard of the type described comprising a top portion having integral outwardly convex fingers projecting from said top portion at predetermined spaced intervals peripherally 20 thereof and arranged so that the maximum diameter of said outwardly convex fingers in their normal static relation is greater than the diameter of the top portion, said top portion having an opening of predetermined irregular configuration 25 located centrally therein for reception of a lifting tool, the cross section of a portion of which corresponds to the irregular configuration of the opening in the top portion.

2. A valve guard of the type described comprising a disk like top portion having integral outwardly convex fingers of substantial length and width projecting approximately at right angles from said top portion at predetermined spaced intervals peripherally thereof and arranged so that the maximum diameter of said slightly convex fingers in their normal static relation is greater than the diameter of the top portion, said top portion having an opening of predetermined irregular configuration located 30 centrally therein for the reception of a lifting tool, the cross section of a portion of which corresponds to the irregular configuration of the opening in the top portion.

3. A valve guard of the type described comprising a top portion having integral outwardly convex fingers projecting from said top portion at predetermined spaced intervals peripherally 45 thereof and arranged so that the maximum diameter of said outwardly convex fingers in their 50 normal static relation is greater than the diameter of the top portion, said top portion having an opening of predetermined irregular configuration located centrally therein for reception of a lifting tool, the cross section of a portion of which 55 corresponds to the irregular configuration of the opening in the top portion, and means overlying said top portion concealing the said opening therein.

4. A valve guard of the type described comprising a top portion having integral outwardly convex fingers projecting from said top portion at predetermined spaced intervals peripherally 60 thereof and arranged so that the maximum diameter of said outwardly convex fingers in their 65 normal static relation is greater than the diameter of the top portion, said top portion having an opening of predetermined irregular configuration located centrally therein for reception of a lifting tool, the cross section of a portion of which 70 corresponds to the irregular configuration of the opening in the top portion, and destructible means secured to the upper surface of said top portion to conceal the said opening therein.

5. A valve guard of the type described com- 75

- prising a disk like top portion having integral outwardly convex fingers of substantial length and width projecting approximately at right angles from said top portion at predetermined spaced intervals peripherally thereof and arranged so that the maximum diameter of said slightly convex fingers in their normal static relation is greater than the diameter of the top portion, said top portion having an opening of predetermined irregular configuration located centrally therein for the reception of a lifting tool, the cross section of a portion of which corresponds to the irregular configuration of the opening in the top portion, and destructible means secured to the upper surface of said top portion to conceal the said opening therein.
6. In a casing comprising a narrow neck portion and a lower housing portion having a valve located therein, and guard means removably located in the neck portion of said casing and extending inwardly of said housing portion to normally prevent access to and operation of the valve through said neck portion.
7. In a casing comprising a narrow neck portion and a lower housing portion having a valve located therein, and guard means removably located in the neck portion of said casing and extending inwardly of said housing portion to normally prevent access to and operation of the valve through said neck portion, said guard means comprising a top portion having integral outwardly convex fingers extending outwardly from said top portion at predetermined spaced intervals peripherally thereof and arranged so that the maximum diameter of said convex fingers is greater than the diameter of said top portion for engagement with the walls of the neck portion of said casing.
8. In a casing comprising a narrow neck portion and a lower housing portion having a valve located therein, and guard means removably located in the neck portion of said casing and extending inwardly of said housing portion to normally prevent access to and operation of the valve through said neck portion, said guard means having an opening of predetermined irregular configuration located centrally in the top thereof for the reception of a lifting tool, the cross section of a portion of which corresponds to the irregular configuration of the opening in said guard means.
9. In a casing comprising a narrow neck portion and a lower housing portion having a valve located therein, and guard means removably located in the neck portion of said casing and extending inwardly of said housing portion to normally prevent access to and operation of the valve through said neck portion, said guard means having an opening of predetermined irregular configuration located centrally in the top thereof, and a tool having a portion the cross section of which corresponds to the irregular configuration of the opening of said guard means arranged for insertion through said opening to engage the guard means so that the latter may be withdrawn from the neck portion of the casing, and destructible means secured to the upper surface of said top portion to conceal the opening therein.
- top thereof, and a tool having a portion the cross section of which corresponds to the irregular configuration of the opening of said guard means arranged for insertion through said opening to engage the guard means so that the latter may be withdrawn from the neck portion of the casing.
10. In a casing comprising a narrow neck portion and a lower housing portion having a valve located therein, and guard means removably located in the neck portion of said casing and extending inwardly of said housing portion to normally prevent access to and operation of the valve through said neck portion, said guard means comprising a top portion having an opening therein and integral outwardly convex fingers extending outwardly from said top portion at predetermined spaced intervals peripherally thereof and arranged so that the maximum diameter of said convex fingers is greater than the diameter of said top portion for engagement with the walls of the neck portion of said casing, and destructible means secured to the upper surface of said top portion to conceal the opening therein.
11. In a casing comprising a narrow neck portion and a lower housing portion having a valve located therein, and guard means removably located in the neck portion of said casing and extending inwardly of said housing portion to normally prevent access to and operation of the valve through said neck portion, said guard means having an opening of predetermined irregular configuration located centrally in the top thereof for the reception of a lifting tool, the cross section of a portion of which corresponds to the irregular configuration of the opening in said guard means, and destructible means secured to the upper surface of said top portion to conceal the opening therein.
12. In a casing comprising a narrow neck portion and a lower housing portion having a valve located therein, and guard means removably located in the neck portion of said casing and extending inwardly of said housing portion to normally prevent access to and operation of the valve through said neck portion, said guard means having an opening of predetermined irregular configuration located centrally in the top thereof, and a tool having a portion the cross section of which corresponds to the irregular configuration of the opening of said guard means arranged for insertion through said opening to engage the guard means so that the latter may be withdrawn from the neck portion of the casing, and destructible means secured to the upper surface of said top portion to conceal the opening therein.

WILLIAM H. BUCK.
